CLAIM

The ornamental design for an air filtration unit housing for use with laser surgery, as shown and described.

DESCRIPTION

FIG. 1 is a top perspective view of an air filtration housing for use with laser surgery showing my new design;

FIG. 2 is a front end elevation view thereof;

FIG. 3 is a rear end elevational view thereof;

FIG. 4 is a top plan view thereof;

FIG. 5 is a right side elevational view thereof;

FIG. 6 is a left side elevational view thereof; and

FIG. 7 is a bottom plan view thereof.
